DESIGN FOR A COMBINATION DRAWING INSTRUMENT

Peter J. Bakallie, New York, N. Y.

Application April 14, 1939, Serial No. 84,273

Term of patent 14 years

To all whom it may concern:

Be it known that I, Peter J. Bakallie, a citizen of the United States and a resident of New York city, in the county of New York and State of New York, have invented a new, original, and ornamental Design for Combination Drawing Instruments, of which the following is a specification, reference being had to the accompanying drawing, forming a part thereof.

The figure is a perspective view of a combination drawing instrument, showing my new design.

The back of the instrument is smooth and plain.

I claim:

The ornamental design for a combination drawing instrument, as shown and described.

PETER J. BAKALLIE.
